(57) **CLAIM**

We claim the ornamental design for an information handling system bezel having multi-angled reflective surfaces, as shown and described.

DESCRIPTION

FIG. 1 is a front perspective view of the information handling system bezel having multi-angled reflective surfaces;

FIG. 2 is a front elevation view thereof;

FIG. 3 is a rear elevation view thereof;

FIG. 4 is a right side view thereof;

FIG. 5 is a left side view thereof;

FIG. 6 is a top view thereof;

FIG. 7 is a bottom view thereof;

FIG. 8 is a front perspective view of the information handling system bezel having multi-angled reflective surfaces shown with environment;

FIG. 9 is a partial front left perspective view thereof shown at an enlarged scale with light reflected from a light source aligned at a first angle;

FIG. 10 is a partial front left perspective view thereof shown at an enlarged scale with light reflected from a light source aligned at a second angle;

FIG. 11 is a partial front left perspective view thereof shown at an enlarged scale with light reflected from a light source aligned at a third angle; and,

FIG. 12 is another partial front left perspective detail view thereof shown at an enlarged scale with light reflected from a light source aligned at a fourth angle.

The stipple shading in FIGS. 1-12 illustrates a change in appearance on the angled surfaces as they reflect light from a light source at different angles.

(Continued)

The broken lines showing the rest of the information handling system in FIG. 8 illustrate environment that forms no part of the claimed design. The broken lines along the right and bottom edges of FIGS. 9-12 illustrate boundaries of the figures and form no part thereof.
